UNITED STATES PATENT OFFICE

2,438,805

COMBINED STRAND DISPLAY AND
TRANSFER REEL

Egbert P. Hoyle, Cortland, N. Y., assignor to
Cortland Line Company, Inc., Cortland, N. Y.,
a corporation of New York

Application September 18, 1946, Serial No. 697,633

3 Claims. (Cl. 242—118)

1

The present invention relates to a compact sectionalized spool means embodying three separable parts disposed as a marketing casing or jacket of the transparent reel type serving to attractively exhibit a coil of high grade fish line or the like strand product whereby to conjointly offer for sale to the sporting goods trade, such commodity as a unit with its display jacket. A rearrangement of component parts also allows my container to be utilized as a strand transfer reel.

One reel section comprises a reversible dished cover or hood adapted in one of its operative positions, to protectively seal a stowed coil against dust, excess moisture or other contamination, and in an alternative position serves as a guide flange of my transfer reel.

Said reel casing may further include a non-circular socketed base section and a cooperating cap section provided with an eccentric plug adapted to be easily brought into interlocked wedged engagement within the base socket by a rotative manipulative twist in accordance with the teachings of the Allen and Womeldorf Patent No. 2,124,512 issued July 19, 1938.

The object of my invention is to provide for a neatly refined coil reel of the indicated character of which all its parts may be economically fabricated and furnished with each sold coil without unduly increasing the factory cost of such combined display unit.

Embodied herein are also certain structural features organized to promote the end in view, and all of which will hereinafter be more explicitly set forth.

Reference is had to the accompanying one sheet of drawings which are illustrative of a preferred exemplification, and in which drawings:

Fig. 1 represents a top or cover view of my container assembly having a coiled fish line stowed therein; and Fig. 2 shows a cross-section of such assembly taken along 2—2 of Fig. 1.

Fig. 3 is a bottom view of said assembly; and Fig. 4 a fragmental cross-sectional view taken along 4—4 of Fig. 2.

The disclosed style of container reel comprises three separable parts respectively designated 10, 20 and 30, that may respectively be fabricated from moulded transparent plastic stock. The base section 10 is preferably kept relatively thin and uniform in stock thickness. This light weight base is shaped to provide for a disc flange 11 whose perimeter may be reenforced as at 12 and have a circular centering ledge 13 therearound.

2

The disc center may be perforated to provide for a spindle receiving aperture 14. In circumscribing relation to such aperture, is integrally formed a cross-sectionally hollow flange spacer agency or offset annulus 15 of which the interior wall 16 is given an elliptical socket shape or bore 25 provided with a major and a minor axis of unequal dimensions. The exterior wall 17 of said annulus may be kept truly cylindrical and have a ring-like tie wall 18 disposed parallel to the flange 11. Distributed radial webs such as 19 may be inset to laterally stiffen such base structure as a whole.

A second part of my container comprises the cap section 20 provided with a non-circular flange 21 that is centrally perforated at 22 in registry with the disc aperture 14. The perimeter of the manipulative flange 21 may be given a round cornered substantially square contour of which the flats are preferably kept materially smaller than the diametral dimension of the flange 11. A circular fish line identifying label may be affixed to the exposed side face of the cap flange 20 within the marginal confines thereof and provided with a centralized hole that clears the perforation 22 to admit a suitable reel spindle therethrough without label mutilation.

Affixed to the opposite side of the cap flange 20 is an upstanding tubular plug 23 of which the endless wall contour is given an elliptical profile shaped to enter into the socket bore 25 and initially leave a restricted clearance gap 24 therebetween. A partial rotation on part of the flange 21 serves to frictionally interlock the plug 23 into said bore. A reversed turning of said plug permits of its unobstructed withdrawal.

A demountable third part of my container comprises a cross-sectionally dished hood or cup shaped cover section 30 of thin plastic including a dual faced, ring-shaped basal wall 31 of which its centralized hole is sized to freely telescope about the plug 23 as shown in Fig. 2. In one of its alternative positions, the skirted hood brim 32 is made to snugly engage the ledge 13 of the base section to form a seal therewith when used as a protective container. The inner region of the reversible wall 31 is interposed to clamp between a tie wall face of the annulus 15 and the marginal region of the cap flange 21. For stowage needs, the coiled fish line 33 may be mounted over the exterior wall 17 of the base annulus and within the confines of the hood brim 32.

By releasing the plug interlock, said brim may be reversely disposed into its dotted Fig. 2 position 32', it being pointed out that the same plug

interlock means serves to retain the rearranged cover 30 in such reversed position.

As a further refinement, the eccentric contour of my bore wall 16 has been improved over the showing of the aforesaid Patent #2,124,512 in the Fig. 3 fashion to provide for a pair of opposed interior stop abutments such as 34. As defined in Fig. 1, the cooperating exterior surface of the cylindrical plug 23 is herein equipped with a pair of radially raised stop projections or lugs such as 26 which may be symmetrically formed by the use of a centralized radius R_1 and an eccentrically offset radius R_2 as indicated. The exposed face of the cap flange 21 may be inscribed with the reversed directional legends (see Fig. 1) to facilitate a positive one way locking or of unlocking the warped plug 23 with respect to its bore.

The arrowed direction represented in the Fig. 4 assembly, brings about a plug interlock by rotatively separating the stop projection 26 relative to the bore abutment 34. Upon close approach in a reversed direction, the initially divided gaps 24 are with certainty made to extend continuously around the plug perimeter in endless formation to freely clear the plug for unobstructed withdrawal from its bore or replacement therein. As an important advantage inherent in my bore and plug refinements, the reel parts are prevented from being improperly reassembled or awkwardly manipulated.

My reel parts are devoid of clips, springs, screw threads or the like complications that would prove inappropriate for moulding such assembled parts from plastic. Furthermore, my container is rendered pleasing in appearance and otherwise affords a neat jacket trim in which to display and promote the sale of coiled strand goods. It may further be emphasized that the use of thin transparent plastic parts visualizes the quality, finish and strand size for selection by a prospective buyer without exposure to dust or the like defilement.

The described preferred embodiment will make apparent to those skilled in this art, the advantages afforded by my simple and relatively cheap combined stowage and transfer reel, it being understood that certain structural changes may be resorted to in attaining a like result, all without departing from the spirit and scope of my invention as more particularly characterized in the appended claims.

I claim:

1. A three-part strand container and combined transfer reel comprising a pair of separable flanges mounted for relative rotation about a common axis, mated spacer means interposed to retain said flanges in definite lateral relationship, said means comprising an annulus having a non-circular bore disposed around said axis and fixedly carried by the inner face of one such flange, a plug component fixedly carried by the inner face of the other flange and having an eccentric superficial contour that is telescoped within and cooperatively shaped with respect to the aforesaid bore to initially provide for a radial clearance gap therebetween, said gap being progressively reduced when said flanges are rotated relative to each other thereby bringing said plug contour into wedged tangential interlock with said bore, and a demountable cup-shaped cover member comprising a reversible dual faced basal wall of ring-shape sized to receive said plug

therethrough and having its inner marginal edge region clamped between the annulus and the aforesaid other flange and which basal wall is retained in either of its positions by the plug when wedgingly interlocked with said bore.

2. A three-part strand container and combined transfer reel comprising a pair of separable flanges mounted for relative rotation about a common axis, mated spacer means interposed to retain said flanges in definite lateral relationship, said means comprising an annulus having a non-circular bore disposed around said axis and fixedly carried by the inner face of one such flange, a plug component fixedly carried by the inner face of the other flange and having an eccentric superficial contour that is telescoped within and cooperatively shaped with respect to the aforesaid bore to initially provide for a radial clearance gap therebetween, said gap being progressively reduced when said flanges are rotated relative to each other thereby bringing said plug contour into wedged tangential interlock with said bore, and a reversible cup-shaped cover comprising a substantially flat basal wall component having a centrally disposed aperture sized to receive said plug therethrough and further having a perimetrical complete skirt component of which the brim abuts the marginal edge of the aforesaid one flange to serve as a container and which basal wall when reversely faced serves as a transfer reel component, said basal wall in either of its positions being retained in place by said plug when interlockingly wedged into engagement with said bore.
3. A three-part strand container and combined transfer reel comprising a pair of separable flanges mounted for relative rotation about a common axis, mated spacer means interposed to retain said flanges in definite lateral relationship, said means comprising an annulus having a non-circular bore disposed around said axis and fixedly carried by the inner face of one such flange, a plug component fixedly carried by the inner face of the other flange and having an eccentric superficial contour that is telescoped within and cooperatively shaped with respect to the aforesaid bore to initially provide for a radial clearance gap therebetween, said gap being progressively reduced when said flanges are rotated relative to each other thereby bringing said plug contour into wedged tangential interlock with said bore, and a reversible cup-shaped member fabricated from transparent material to comprise a dual faced basal wall component of ring shape of which the inner region is interposed between the annulus and the aforesaid other flange, said interposed ring region being interlockingly gripped in place by one and the same plug irrespective of which ring face is positioned upon the annulus.
